[57] CLAIM

The ornamental design for an air blower, substantially as shown and described.

DESCRIPTION

FIG. 1 is a right side elevational view of an air blower embodying my new design, the left side being a mirror image of the right side shown;

FIG. 2 is a top plan view thereof;

FIG. 3 is a front elevational view thereof; and

FIG. 4 is a rear elevational view thereof.

*Fig. 1**Fig. 2**Fig. 3**Fig. 4*
